(57) CLAIM

The ornamental design for a bracelet, as shown and described.

DESCRIPTION

FIG. 1 is a perspective of my invented bracelet design.

FIG. 2 is a top plan view thereof.

FIG. 3 is a side elevation view thereof; and,

FIG. 4 is a bottom plan view thereof.

The portions shown in broken lines which includes the gemstones shown in FIG. 2 form no part of the claim design.

1 Claim, 3 Drawing Sheets

FIG. 1

FIG. 2

FIG. 3
